CLAIM

We claim the ornamental design for a fixture for gas canister, as shown and described.

DESCRIPTION

FIG. 1 is a perspective view of the fixture for gas canister.
FIG. 2 is a front view thereof.
FIG. 3 is a rear view thereof.
FIG. 4 is a side view thereof.
FIG. 5 is a side view thereof.
FIG. 6 is a top view thereof.
FIG. 7 is a bottom view thereof; and,
FIG. 8 is a perspective view thereof showing surrounding environment thereof.

(Continued)

The broken line showing of a gas canister is included for the purpose of illustrating an environment of use and forms no part of the claimed design.

1 Claim, 4 Drawing Sheets
